UNITED STATES PATENT OFFICE.

SIDNEY C. GAUNT, OF CHICAGO, ILLINOIS, ASSIGNOR TO BARNHART BROS. & SPINDLER, OF CHICAGO, ILLINOIS, A CORPORATION OF ILLINOIS.

DESIGN FOR A FONT OF TYPE.

51,374.

Specification for Design.

Patented Oct. 16, 1917.

Application filed May 4, 1917. Serial No. 166,476. Term of patent 7 years.

To all whom it may concern:

Be it known that I, SIDNEY C. GAUNT, a citizen of the United States, residing at Chicago, in the county of Cook and State of Illinois, have invented a new, original, and ornamental Design for a Font of Type, of which the following is a specification, reference being had to the accompanying drawing, forming a part thereof.

The drawing is a view of the characters of a font of type showing my new design.

I claim:

The ornamental design for a font of type, as shown.

SIDNEY C. GAUNT.

Witnesses:

A. L. JONES,
O. M. WERMICH.
